UNITED STATES PATENT OFFICE.

HENRY H. MORETON, OF VENICE, CALIFORNIA.

ELECTRICAL HEATER.

1,416,963.

Specification of Letters Patent. Patented May 23, 1922.

Application filed July 30, 1920. Serial No. 399,981.

To all whom it may concern:

Be it known that I, HENRY H. MORETON, a citizen of the United States, residing at Venice, in the county of Los Angeles and 5 State of California, have invented a new and useful Electrical Heater, of which the following is a specification.

This invention is a heater of the type in which a parabolic reflector is employed, to 10 project the heat rays into the space to be heated.

One of the objects of the invention is to provide a heater of the parabolic type, having means whereby it may be attached 15 to and supported by a standard electric lamp socket. A further object is to provide means whereby the parts may be relatively adjusted to bring the heat unit and the reflector into focus.

20 The invention will be hereinafter fully set forth and particularly pointed out in the claims.

In the accompanying drawing:

Figure 1 is a side elevation, partly in section, illustrating a heater constructed in accordance with the invention. Figure 2 is a top plan view of the reflector, illustrating means for attaching the same to a lamp socket. Figure 3 is a side elevation, illustrating a slight modification. Figure 4 is a side elevation, illustrating a second modification. Figure 5 is a view illustrating a method of supporting a plurality of heaters.

Referring to Figures 1 and 2, 10 designates an electric lamp socket, which may be of any standard construction. The reflector 11, is of the well-known parabolic type, provided with a central opening 12, and having attached to it in register with said opening, a split collar 13, provided with a clamping screw 14. The split collar 13, may be attached to the reflector 11 in any desired manner, the drawing illustrating the parts as connected by rivets. The heating 15 unit 15, is of a type commonly employed in electric heaters being constructed of an approximately cylindrical body of insulating material, provided with a wrapping of resistance material, one end of said unit being provided with a threaded plug-like portion 16, shaped to engage the threaded shell 17 of the lamp socket. The heat unit is provided with a central contact 18 and a shell contact 19, similar to the contact employed in the standard plugs used in connection with lamp sockets.

In practice, the reflector 11 is first attached to the lamp socket 10, by means of the split sleeve 13. The heat unit 15 is then passed through the opening 12, and screwed 60 into the threaded shell 17 of the lamp socket. The split sleeve 13 permits of an adjustment of the reflector 11, longitudinally of the shell of the lamp socket 10, to bring the reflector into focus with the heat- 65 ing unit, the clamp screw 14, being tightened when the proper adjustment is obtained, so as to retain the reflector in its adjusted position.

In lieu of employing the split ring 13, 70 the reflector 11 may be provided with a flanged sleeve 20, shaped to fit within a standard shade ring 21, of a type commonly attached to standard lamp sockets, the reflector being supported by screws 22, carried by the shade ring in a well-known manner. See Figure 3.

In the form of the invention illustrated in Figure 4, a socket 25 is provided, having a flange 26, secured to the heat reflector 27, 80 said socket having a threaded portion capable of receiving a complementary portion 28, of a heating unit 29. The upper end of the heating unit 29 is formed as a plug 30, capable of engaging the threaded shell of the 85 ordinary standard lamp socket, suitable means being provided to complete the circuit between the contact of the socket and the resistance element of the heating unit. If desired, the shell 25 may be of a well-known 90 construction provided with means which regulates the amount of current used in the heater.

In Figure 5 is diagrammatically illustrated a three plug fixture 35, having two 95 heaters 36 and 37 attached thereto and also a lamp 38, whereby a single fixture is provided, capable of producing both heat and light.

From the foregoing description, it will 100 be readily understood that a simple and inexpensive form of heater of the parabolic type is provided, the same having means whereby the parts may be attached to and supported by a standard lamp socket, thereby avoiding the necessity of employing standards or other supports.

Having thus explained the nature of the invention and described an operative manner of constructing and using the same, 110 although without attempting to set forth all of the forms in which it may be made, or

all of the forms of its use, what is claimed is:—

- 5 1. A heater of the character described comprising a parabolic reflector, a heating unit, and means whereby both may be connected to and supported by a standard lamp socket.
- 10 2. A heater of the character described comprising a parabolic reflector, and a heating unit having means at one end whereby it may be electrically connected with a standard lamp socket.
- 15 3. A heater of the character described comprising a parabolic reflector, a heating unit having means at one end whereby it may be electrically connected to and supported by a standard lamp socket, and means whereby said reflector and said heating unit may be held in juxtaposition with each other.
- 20 4. A heater of the character described comprising a parabolic reflector, an approximately cylindrical support member, and a heating element carried thereby, said support member being adjustable relative to the reflector, whereby the heating element may be brought to proper focal position.
- 25 5. A heater of the character described comprising a parabolic reflector having a split sleeve capable of engaging a standard lamp socket, and a heating unit having means whereby it may be electrically connected with said socket in juxtaposition with said reflector.
- 30 6. A heater of the character described comprising a parabolic reflector having a sleeve, and a heating unit extended longitudinally through said sleeve and having means whereby it may be electrically connected with a standard lamp socket.
- 35 7. A heater of the character described comprising a parabolic reflector having a sleeve, a heating unit screwed within said sleeve and having means whereby it may be electrically connected with a standard lamp socket.
- 40 8. A heater of the character described comprising a parabolic reflector, and an ap-
- proximately cylindrical heating unit having its axis coincident with the axis of said reflector. 50
9. A heater of the character described comprising an approximately cylindrical heating unit having means at one end whereby it may be electrically connected with a socket, and a parabolic reflector in juxtaposition with said heating unit and having a supporting sleeve concentric with said unit. 55
10. A heater of the character described comprising a parabolic reflector, an approximately cylindrical heating unit having its axis coincident with the axis of said reflector, and means whereby said heating unit may be electrically connected with a standard lamp socket. 60
11. A heater of the character described comprising a fixture having means for providing a plurality of circuits, and heating units and lighting units attached to said fixture and connected with the respective circuits. 65
12. A heater of the character described comprising a fixture having means for providing a plurality of circuits, a plurality of spaced apart heating units attached to said fixture, and an intermediate lighting unit also attached to said fixture, said heating units and said lighting unit being connected with the respective circuits. 70
13. A heater of the character described comprising a parabolic reflector, a heating unit, and means whereby both may be connected to a standard lamp socket, said reflector and said heating unit being relatively adjustable to bring them into focus. 75
14. A heater of the character described comprising a parabolic reflector, and an approximately cylindrical heating unit having its axis coincident with the axis of the reflector, said heating unit and said reflector being relatively adjustable to bring them into focus. 80
- 45 In testimony whereof I have hereunto set my hand. 85

HENRY H. MORETON.
